[57] CLAIM

The ornamental design for a combined fluorescent lan-
tern and clip, as shown and described.

DESCRIPTION

FIG. 1 is a side elevational view of a combined fluores-
cent lantern and clip showing my new design, the oppo-
site side being a mirror image of the side shown but for
the omission of the switch on the side of the lantern;
FIG. 2 is a front perspective view thereof;
FIG. 3 is a rear elevational view thereof;
FIG. 4 is a bottom plan view thereof;
FIG. 5 is a top plan view thereof;
FIG. 6 is a cross-sectional view thereof as taken along
line 6—6 of FIG. 1.

FIG. 1

FIG. 2

FIG. 6

FIG. 3
